UNITED STATES PATENT OFFICE.

STEPHEN B. GRAY, OF JACKSONVILLE, ILLINOIS; BARTLETT S. GRAY EXECUTOR OF SAID
STEPHEN B. GRAY, DECEASED.

VARIABLE-DRIVE MECHANISM.

No. 926,060.

Specification of Letters Patent. Patented June 22, 1909.

Application filed September 13, 1906, Serial No. 334,383. Renewed April 26, 1909. Serial No. 492,314.

To all whom it may concern:

Be it known that I, STEPHEN B. GRAY, a resident of Jacksonville, in the county of Morgan and State of Illinois, have invented 5 certain new and useful Improvements in Variable-Drive Mechanism, of which the following is a full, clear, and exact description.

The invention relates to variable drive 10 mechanism.

The invention designs to provide an improved construction for a variable pulley embodying a screw-adjustment for the rim-sections.

15 The invention further designs to provide improved variable drive-mechanism comprising a pair of pulleys having screw-adjusted rim-sections and means for simultaneously adjusting the pulleys for different speeds. 20 The invention also designs to provide an adjustable pulley of improved construction and variable drive-mechanism of improved construction.

The invention consists in the several novel 25 features hereinafter set forth and more particularly defined by claims at the conclusion hereof.

In the drawings: Figure 1 is a horizontal section taken through the centers of the pulleys of a variable speed-mechanism, embodying 30 the invention. Fig. 2 is a central vertical section taken on line 2—2 of Fig. 1. Fig. 3 is a side elevation. Fig. 4 is a section on line 4—4 of Fig. 1. Fig. 5 is a cross-section 35 on line 5—5 of Fig. 3.

Variable speed-mechanism of the type herein involved usually comprises a pair of adjustable pulleys connected together by a belt. The mechanism shown comprises pulleys A and A' of like construction, connected 40 to be driven, one from the other, by a belt B. The pulleys may be mounted upon a frame C of any suitable construction.

The body of the improved pulley comprises hubs 10, one at each side of the pulley, each having a hollow spindle 11 secured thereto. A pulley-side 12 is secured to each hub as at 13 and a drum 14 has its ends secured to the pulley-sides respectively as at 15 50 to secure the hubs and sides together. Rim-sections 16 are each adjustably connected to the body of the pulley by a screw or screw-threaded rod 17 which has its outer end journaled in a bracket 18 and its inner end

in a lug 19, integrally formed with one of 55 the pulley-sides. Screws 17 are radially disposed and extend through correspondingly screw-threaded openings in the rim-sections and thereby the sections may be adjusted radially and positively when the screws are 60 turned. Each of the screw-rods 17 has secured to its inner end within drum 14 a beveled pinion 21.

Simultaneous and equidistant rotation of all of the screws 17 is necessary in adjusting 65 the rim-sections. Screws 17 of each series are simultaneously rotated by a gear-ring 22, having teeth 23 which mesh with pinions 21 which are secured to the inner ends of the screws. This gear-ring is revolvable with respect to the wheel, is mounted in 70 the wheel-drum 14 and is held against lateral displacement by lugs 24. Gear-rings 22 for the pulley-sides respectively are simultaneously rotated with respect to the wheel by 75 a gear-mechanism comprising a gear-wheel 25 mounted on a shaft 26 which is journaled in bearings 27 secured to the drum 14. At either side of gear 25 is mounted a pinion 28 with which it intermeshes. Each pinion 80 28 is mounted on a shaft 29 journaled in bearings 30 and 31 fixed in the drum and is secured to drive a beveled pinion 32 which meshes with a series of teeth 33 formed on the inner face of one of the gear-rings 22. 85 Rotation of gear-wheel 25 will, by means of pinions 28 and 32, cause the gear-rings 22 to be rotated with respect to the wheel and resultantly operate all of the pinions 21 of the wheel to simultaneously and equidistantly 90 rotate all of the screws 17 which will effect equidistant and simultaneous shifts of the rim-sections, in either direction, according to the direction in which the gear 25 is rotated. 95

In variable drive-mechanism embodying a connected pair of pulleys, the size of the rims thereof are increased and decreased respectively and simultaneously. The mechanism for simultaneously operating the gear-trains of the pulleys whereby the size of one will be increased and the size of the other correspondingly decreased, comprises an endless chain D operatively connected to a sprocket-wheel 35 in each of the pulleys and 100 which are connected to rotate wheels 25 of the gear-trains for the adjusting mechanisms. The chain D consists of a series of 105

links 36 having enlarged ends 37 fitting into socket-links 38, the links of the chain being so formed as to permit the revolution of one link with respect to another, *i.e.*, to form a series of links connected by swivel or universal joint to permit a portion thereof to rotate while another portion of the chain is stationary. The purpose of the universal joint chain is to permit those portions of the chain which are held in sprocket-wheels 35 to revolve with the pulleys while the longitudinally extending portions of the chain are stationary. The chain extends through hollow spindles 11 in each of which an oil-pocket or recess 41 is formed and extends at one side through a tubular guide or casing 40 and from the spindle of one of the pulleys to and through the spindle of the other pulley. The other side of the chain extends from the hollow spindle 11 of one of the pulleys through a stationary guide or housing 42 in which is arranged a sprocket-wheel 43 around a portion of which the chain extends so the chain can be shifted longitudinally in its guides to rotate sprocket-wheels 35 to operate the gear-trains in the pulleys to adjust the rim-sections of the pulleys. Chain-guide 40 is also stationary and the portions of the chain in engagement with sprocket-wheels 35 are held in engagement with the teeth of said wheels in the wheel-drum 14 by curved guides 44. Chain-guides 40 and 42 are usually formed of sections fitting together to inclose the chain and sprocket-wheel 43. Several sectional links 38' may be provided for convenience in applying the chain. Sprocket-wheel 43 for shifting the chain to adjust the pulleys is secured to a shaft 46 mounted in bearings 47 and 48 which may be connected to the frame C in any suitable manner. A hand-wheel 49 is secured to the upper end of the shaft so it can be manually rotated. The sprocket-wheel may be operated or controlled by any suitable means and if desired to operate the shaft 45 from some other point, a sprocket-wheel 50 may be provided which may be connected in any suitable manner to a lever or handle at any desired point.

To compensate for the differences in the straight reach of belt when the pulleys are set in different positions, and to take up any slack in the belt, an idler-pulley 51 is provided which serves to keep the belt taut at all times. Idler 51 is connected to a shaft 52 which is journaled in bearings 53, secured to supporting-bars 54 which are pivotally sustained as at 55. When the pulley-rims are substantially the same in diameter, the straight portion of the reach of the belt is somewhat less than when the pulley-rims are materially different in size and for the purpose of compensating for this difference or variation, a differential pressure mechanism is provided for the idler or tightener.

This mechanism comprises a lever 56 pivoted as at 57 to the frame, having its free end connected to one end of the idler-supporting lever 54 by a spring 58 which is adapted to take up any variation in the belt length and to keep the belt taut. Said mechanism also comprises a collar 60 connected by screw-thread 61 to the controller-shaft 46. Collar 60 is connected by a link 62 to an arm 63 which is connected to a rock-shaft 64 having arms 65, one at each side of the frame, provided with rollers 66 at their lower ends which are adapted to engage cams 67, one of which is secured to each of the levers 56. Cams 67 are shaped to allow lever 56 to be positioned so that the idler 51 will be held by spring 58 in proper relation with respect to the belt without substantial variation of the pressure of the idler against the belt. In other words, this mechanism provides a tension-device for the idler which is adjustable to compensate for the various positions of the belt and its different positions as the pulleys are adjusted. Collar 60 being connected to the controller-shaft which operates the mechanism for adjusting the pulleys, is simultaneously adjusted to shift arms 65 so the cams 67 will allow the idler and tension-device to be simultaneously adjusted in accordance with the adjustment of the pulleys.

The operation of the improved mechanism will be as follows: Assuming one of the pulleys to be driven from any suitable source, and the belt B held in operative relation with both pulleys it will transmit power from one pulley to the other, the pulleys with their adjustable rim-sections and the gear-mechanism in each pulley revolving therewith. Those portions of the adjusting-chain D which extend around the sprocket-wheels in the pulley, will revolve with the wheel and sprocket the universal joints between the links of the chain permitting such revolution of such portions of the chain while the other portions of the chain remain stationary. idler 51 being held in engagement with the belt B by the springs 58 of the tension-device will keep the belt taut and compensate for any slight wear or stretch of the belt or variation in belt length as the pulleys are adjusted. When the speed of the driven pulley is to be varied, the operator will turn controller-shaft 46 to which sprocket-wheel 43 is secured, and such rotation will shift the adjusting - chain D longitudinally and effect simultaneous rotation of the sprockets 35 in the pulleys about shafts 26 and operate the gear-trains for the adjustable rim-sections. Gear-wheels 25 will rotate the oppositely disposed pinions 29, 32, to rotate the gear-rings 22 with respect to the pulley. These gear-rings will turn the pinions 21 to which the radial screw-rods 17 are secured and effect equidistant and simultaneous shift

of the rim-sections 16 which are adjustably sustained thereby. The gear-mechanisms of the pulleys and the adjusting-chain respectively are connected to operate the screw-shafts in opposite directions, *i. e.*, when the 5 chain is adjusted to rotate the screw-rod 17 of one pulley to shift the rim-sections thereof inwardly, the gear-mechanism of the other pulley operates the screw-shafts of the latter 10 in opposite direction to correspondingly shift the rim-sections thereof in opposite direction and resultantly as the size of one pulley is increased and other is correspondingly decreased. This adjustment can be effected 15 while the mechanism is in operation. Simultaneously with the adjustment of the pulleys by controller-rod 46, screw-threaded collar 60 on said shaft is shifted longitudinally to adjust arm 65 to allow the levers 56 and 20 idler 51 to adjust themselves according to the position of that portion of the belt with which the idler engages, *e. g.*, assuming that the pulleys are adjusted to be operated at substantially the same speed, the idler adjusting device will be in position indicated in 25 Fig. 3 of the drawings. If the controlling mechanism is operated to adjust the pulleys so they will be materially different in size the straight reaches of the belt will be longer 30 and the arms 65 will be shifted into such relation with respect to cam 57 that arms 56 will move upwardly or yield to allow the idler 51 to maintain the belt under the desired tension. Thus it will be seen that by 35 adjustment of the controller, the screw-rods for both of the pulleys will both be simultaneously operated to adjust the rim-sections and vary the relative size of the pulleys and the idler will be simultaneously adjusted. 40 The invention provides an improved pulley embodying a series of simultaneously and screw-adjusted rim-sections. A screw-adjustment is preferable over other forms because the rims can be adjusted with accuracy 45 and because it is not necessary to provide a pulley with any laterally adjusting elements against which strain is exerted when the belt exerts pressure on the rim. The invention also provides screw-operated adjusting- 50 mechanism for the pulley which can be operated while the pulley is revolving. The invention further provides an improved variable drive-mechanism embodying pulleys having screw-operated adjusting-mechanism 55 and means for simultaneously adjusting both pulleys, and furthermore provides mechanism for such type of pulleys whereby they can be adjusted while the mechanism is in operation. The tension-device for the idler 60 which keeps the belt taut is adjustable simultaneously with the controlling mechanism to avoid unnecessary tension on the belt in its different adjustments. 65

The invention is not to be understood as restricted to the details shown and de-

scribed but may be varied by the skilled mechanic without departing from the spirit and scope of the invention.

Having thus described the invention, what I claim as new and desire to secure by Letters Patent, is:

1. In a pulley, the combination of a body comprising a hollow spindle, a series of adjustable rim-sections, a series of adjusting screws for the sections, mechanism for conjointly operating the screws, and means extending through said spindle for operating said mechanism. 75

2. In a pulley, the combination of a body comprising a hollow spindle, a series of adjustable rim-sections, a series of adjusting-screws for the sections, mechanism for conjointly operating the screws and a chain extending through said spindle for operating said mechanism. 80

3. In a pulley, the combination of a body comprising a hollow spindle for the body, a series of adjustable rim-sections, a plurality of adjusting-screws for the sections, gear-mechanism for conjointly operating the screws to adjust the sections, comprising a toothed wheel mounted to revolve with the pulley, and means for operating the toothed wheel extending through said spindle. 85

4. In variable drive-mechanism, the combination of a pair of pulleys, each comprising a series of adjustable rim-sections, a belt connecting the pulleys, adjustable-screws for the rim-sections, and means for conjointly operating the screws of both pulleys comprising a flexible element operatively connected to both of the pulleys. 95

5. In variable drive-mechanism, the combination of a pair of pulleys each comprising a plurality of adjustable rim-sections, adjusting-screws for the sections, a belt connecting the pulleys, and gear-mechanism connecting the screws of each pulley and revolute with the pulley, and a chain for conjointly operating the gear-mechanism. 105

6. In variable drive-mechanism, the combination of a pair of pulleys each comprising a series of adjustable rim-sections and hollow spindles for the pulley, adjusting-screws for the rim-sections, a belt connecting the pulleys, gear-mechanism for simultaneously operating the screws to adjust the sections, and means for conjointly operating the gear-mechanisms of both pulleys extended through said spindles and connecting 115 said mechanisms respectively. 120

7. In variable drive-mechanism, the combination of a pair of pulleys each comprising adjustable rim-sections, mechanism for conjointly adjusting the sections of the pulleys, a belt connecting the pulleys, a belt-tightener, and means for differentially operating the tightener to correspond with the adjustment of the pulleys. 125

8. In variable drive-mechanism, the com- 130

5 combination of a pair of pulleys each comprising adjustable rim-sections, mechanism for conjointly adjusting the sections of the pulleys, a belt connecting the pulleys, a belt-tightener, a tension-device for the tightener, controlling-means for the adjusting-mechanism, and means for adjusting the tension-device when the pulleys are adjusted.

9. In variable drive-mechanism, the combination of a pair of pulleys each comprising adjustable rim-sections, mechanism for conjointly adjusting the sections of the pulleys, a belt connecting the pulleys, a belt-tightener, a tension-device for said tightener, and a screw for adjusting said tension-device when the pulleys are adjusted.

10. In variable drive-mechanism, the combination of a pair of pulleys each comprising adjustable rim-sections, mechanism for

conjointly adjusting the sections of the pulleys, a belt connecting the pulleys, a belt 20
tightener, a spring for holding the tightener in engagement with the belt and mechanism for adjusting the spring when the pulleys are adjusted. 25

11. In variable drive-mechanism, the combination of a pair of pulleys each comprising a series of adjustable rim-sections, adjusting-screws for the sections, a belt connecting the pulleys, a tension-device for the belt, and mechanism for conjointly adjusting the screws of both pulleys to adjust the rim-sections.
